VALVE MECHANISM

Eugene Martin, Erie, Pa., assignor to The Standard Stoker Company, Incorporated, a corporation of Delaware

Application November 28, 1941, Serial No. 420,775

5 Claims. (Cl. 121—141)

This invention relates to valves for controlling the flow of pressure fluid to a reversible pressure fluid operated engine.

The main object of the invention is to provide a novel and efficient valve mechanism for automatically effecting reversal of a reversible pressure fluid operated engine when the engine stalls due to an overload.

A further object of the invention is to provide a valve mechanism of the type described that will automatically effect reversal of a reversible pressure fluid operated engine when the engine stalls due to an overload; that will effect continued reverse operation of said engine for a predetermined period; and that will automatically effect forward running of the engine upon the expiration of said predetermined period.

More specifically it is an object of the invention to provide an operating and reverse valve for a stoker engine which will automatically effect reversal of the stoker engine for a predetermined period when the stoker conveyor stalls and automatically restore the stoker engine to forward running operation upon the expiration of the said predetermined period.

It is also a further general object of the invention to provide a valve mechanism as above described, that is positive and reliable in its action, consists of relatively few, simply constructed parts, and that can be manufactured at comparatively small cost.

With the above and other objects in view, the invention consists in the improved construction, combination and relative arrangement of the several parts as hereinafter more fully described, claimed and illustrated in the accompanying drawings, and wherein

Fig. 1 is a longitudinal vertical section through the rear portion of a locomotive with a stoker, and a pressure fluid operated engine and valve mechanism for operating the stoker, applied to the locomotive, a part of the stoker being broken away;

Fig. 2 is a central vertical section through the novel valve mechanism, the valve being shown in position for operating the stoker conveyor in forward direction;

Fig. 3 is a central vertical section through the novel valve mechanism, the valve being shown in position for operating the stoker conveyor in reverse;

Fig. 4 is a view in section taken on the line 4—4 of Fig. 3; and

Fig. 5 is a view in section taken on the line 5—5 of Fig. 2.

The invention is illustrated in the drawings and will be described as applied to the stoker engine of a locomotive, but it will be apparent that the novel valve mechanism is equally adaptable to engines for operating other devices and appliances.

Referring specifically to Fig. 1, the locomotive is indicated by the letter L and comprises a frame 10 upon which the boiler backhead 11 is supported by means of an expansion plate 12. A cab deck 13 extends rearwardly from the backhead 11 and is supported at its rearward end on the frame 10 by expansion plate 14.

The stoker is shown at S and includes a fuel discharge conduit 15 supported at its upper end from the backhead 11 by a bracket 16 and at its lower end by a bracket 17. The lower end of the discharge conduit 15 is flexibly connected with and supports the forward end of another conduit 18 leading forwardly from the tender (not shown). A conveyor screw, such as 19, extends through the conduits 15 and 18 and conveys fuel therethrough for delivery into a firebox contained within the boiler. The conveyor screw 19 is operated by means of gearing (not shown) driven by shafting 20 having an operative connection with the stoker drive engine E.

The engine E is of the multi-cylinder, double acting type and utilizes steam or other pressure fluid as an operating medium therefor. The engine is rigidly secured in any suitable manner to the locomotive frame 10. The admission of steam or other pressure fluid to the driving engine E and the exhausting of steam therefrom are controlled by a reversing valve V having an inextensible rod 21 which extends upwardly through the cab deck 13 and terminates in the handle 22 by which the valve V may be manually manipulated.

Steam from the locomotive boiler is conducted to the valve V by means of an intake pipe 23 while the steam exhausted by the engine E passes through the valve V and thence through exhaust pipe 24. During normal forward running operation of the stoker, the valve V conducts steam from the intake pipe 23 to the pipe 25, the latter having a connection with the steam chest 26 of the engine. Steam exhausted from the engine passes through the pipe 27 into the valve V and thence to exhaust pipe 24.

Reversal of the stoker engine E, when the stoker conveyor stalls, and resumption of forward operation after a predetermined interval of time is accomplished automatically in the manner hereinafter described, and manual reversal is accomplished by raising the rod 21. During such

reverse operation the valve V admits steam from pipe 23 to pipe 27, the steam exhausting through pipe 25, valve V and thence through pipe 24.

Referring now to Figs. 2 to 5, inclusive, illustrating the detailed construction of the control valve V, it will be seen that it comprises a body member 28 having axially aligned upper and lower bores 29 and 30, respectively, and bore 31 laterally disposed with respect to lower bore 30. Within the cylindrical bore 29 there is mounted a movable hollow valve element 32 arranged for movement within the body 28 by means of a stem 33 which has an operative pivotal connection as at 34 with the rod 21. The upper end of the valve body 28 is covered by a cap 35 secured to the valve body by studs 36, the cap 35 having a stuffing box 37 through which the stem 33 passes. The movable valve element 32 is in the form of a spool having an upper enlarged end 38 and a lower enlarged end 39. In each enlarged end 38, 39 of the movable valve element 32, rings such as 40 are provided for insuring a pressure-tight seal between the enlarged ends 38, 39 of the valve element and the reduced portion 41 thereof.

The body member 28 is provided at the lower end of the bore 29 with a seat 42 upon which the lower enlarged end 39 of the valve element 32 is adapted to rest, as shown in Fig. 2. Adjacent the lower end 39 of the valve element 32, the stem 33 is provided with a shoulder 43 seating against a central boss 44 which is formed with the valve element 32 and connected to the cylindrical walls thereof by ribs 45. The stem 33 passes through the central boss 44 and its lower end is engaged by a nut 46 drawn tightly against the under side of the boss 44 to form a secure connection between the stem 33 and the movable valve element 32.

A stem 47, threaded in the nut 46, extends downwardly from and in axial alignment with the stem 33, through the wall 48 into the lower bore 30. The open lower end of the bore 30 is provided with a cap nut 49 threaded into the body member 28. The cap nut 49 is provided with a passage 50 in which is disposed a ball check valve 51 effecting one way flow communication from atmosphere into the bore 30. The lower end of the stem 47 carries a piston 52 adapted for slideable movement in the bore 30. A compression spring 53 encircles the stem 47, one end thereof being received in an annular groove 54 in the wall 48 and the other end thereof being received in an annular groove 55 in the piston 52.

In the bore 31 is mounted a movable hollow spool-shaped valve element 56, having an upper enlarged end 57 and a lower enlarged end 58. A cap nut 59 is threaded into the body member 28 in the lower portion of the bore 31 forming a seat for the valve element 56. A plug 60 threaded in the cap nut 59 forms a seat for one end of the compression spring 61, the other end thereof contacting the transverse web 62 within the hollow valve element 56 urging the latter to the position shown in Fig. 2. The pressure of the spring 61 can be adjusted by threading the plug 60 farther in or out of the cap nut 59, and can be secured in adjusted position by drawing the lock nut 63 tightly up against the cap nut 59. The upper end of the enlargement 57 of the hollow valve element 56 is formed with a seat 64 arranged to receive a disc valve 65 which, in the absence of any substantial pressure in the passage 66 connecting bore 31 with port 66, is maintained in an open position by means of a spring 67 encircling the valve stem 68.

Below the seat 39 for the valve element 32, the

valve body 28 is provided with a laterally opening exhaust passage 69 threaded to receive the exhaust pipe 24. A drain passage 70 in the valve body 28 establishes communication between the exhaust passage 69 and the lowermost point of a passage 71 extending vertically along a side of the valve body. Adjacent the lower portion of the passage 71, the valve body is threaded to receive pipe 27 which, during normal stoker operation, conducts exhaust steam from the engine E to the exhaust pipe 24 through the valve V. At the upper portion of the valve body 28 the passage 71 opens inwardly, as at 72, into the bore 29 for conducting the exhaust steam through the valve element 32 during normal stoker operation.

The steam intake pipe 23 is threaded into a boss 13 and admits steam between the enlarged ends 38, 39 of the movable valve element 32 for selective distribution into either of the pipes 25 or 27. As illustrated in Fig. 2, the normal or forward operation of the stoker engine E is attained by moving the valve element 32 to a position in which its lower end 39 rests upon the seat 42. In this position steam passing from the intake 23 enters the bore 29 between the enlarged ends 38, 39 of the valve element 32 and then passes through port 66 into the pipe 25 for admission to the steam chest 26. Under such operating conditions, the pressure of the steam entering passage 65 closes the disc valve 64 against the force of the spring 67, and the compressive strength of the spring 61 is such as to retain the valve element 56 in its upper closed position, as shown in Fig. 2. In the absence of any substantial pressure in port 66, the disc valve is maintained in an open position by means of the spring 67 so that any accumulated condensate in pipes 23, 25 will flow through the hollow valve element 56 and the drain passage 74 before operation of the stoker engine is started.

Occasionally the stoker will stall due to a fuel jam or extraneous material which may have found its way into the conveyor. In such instances it has been the practice to manually operate the reverse valve to reverse the operation of the engine for a few revolutions and then return it to normal operating position. If the jam has not become loosened or extraneous matter dislodged or carried through by the conveyor, the operation of reversing the engine and returning it to forward operation is repeated. My invention, as hereinafter described in detail, provides means whereby the engine is automatically thrown into reverse for a predetermined period when the stoker stalls and then automatically returned to forward running position.

When the stoker engine E stalls due to an overload, steam pressure builds back in the pipe 25 and port 66 and when the pressure has built up to an extent sufficient to move the valve element 56 from the position shown in Fig. 2 to the position shown in Fig. 3, pressure fluid will flow through the passage 65 into the bore 31 and then through the passage 75, connecting the upper end of the bore 31 with the lower end of bore 30, into the bore 30 beneath the piston 52.

The spring 53 is of a strength, preferably, to just overcome friction between the piston 52 and the walls of the bore 30; the valve element 32 and the walls of the bore 29; and the friction of the stuffing box 37, whereby under normal operating conditions movement of the piston 52 and valve element 32 to the position shown in Fig. 2 will be facilitated. Since the spring 53 is only of sufficient strength to overcome friction, pressure

fluid entering bore 30 beneath piston 52 raises the latter and also the valve element 32 to the position shown in Fig. 3. In this latter position of the valve element 32, communication is effected between the intake pipe 23 and the port 72, whereby pressure fluid flows through passage 71 into pipe 27 to the engine E, reversing its operation. In this position of the valve element 32 also, the port 66 communicates through exhaust passage 69 with the exhaust pipe 24, whereupon the spring 61 forces the valve element 56 upwardly to the position shown in Fig. 2, closing off the upper end of passage 75 and trapping pressure fluid in bore 30 beneath the piston 52.

In this latter position of the valve element 56 communication is provided between a port 76 and bleed valve 77 through the enlarged ends 57 and 58 of valve element 56, permitting the trapped pressure fluid to escape slowly. The escape of pressure fluid can be regulated by a threaded nut 78 to retain the piston 52 and valve element 32 in its upper position for a predetermined period and thereby permitting reverse operation of the stoker engine E for a predetermined period. When the pressure beneath the piston 52 has been sufficiently reduced, the valve element 32 will return first to a neutral position cutting off the flow of pressure fluid from intake pipe 23 to both pipes 25 and 27, and then to its normal forward running position providing communication between intake pipe 23 and pipe 25.

If it is desired to manually move the valve element 32 to neutral position, the operator grasps handle 22, turns and raises it and engages keeper 79 in notch 80, and similarly engages keeper 79 in notch 81 to move the valve element 32 into position for reversing the stoker engine. The rod 21 slides freely in handle 22 during automatic operation of the valve.

For purpose of illustration, let it be assumed that valve 82 in pressure fluid intake line 23 (see Fig. 1), is set to admit pressure fluid at 25 pounds from the high pressure side of the line and let it be further assumed that the stoker engine E normally operates the stoker at 25 pounds pressure. The pressure of spring 61 is such that under normal forward running operation of the stoker engine, the valve 56 closes the passage 65, as shown in Fig. 2.

Now let it be assumed that a hard lump of coal or other obstruction has caused the stoker to stall. Pressure will build up in the line 25 causing the valve 56 to move downwardly to the position shown in Fig. 3 against the pressure of spring 61. In order to avoid downward movement of valve 56, and consequent reversal of the stoker engine, each time the stoker engine labors, the pressure of the spring 61 is adjusted to resist opening or downward movement of valve 56 until the pressure in line 25 has built up to about 40 pounds.

When the pressure in line 25 has built up to 40 pounds, and valve 56 opens, pressure fluid passes through passage 75 into bore 30 beneath the piston 52, effecting upward movement of piston 52 and consequently upward movement of valve element 32 to the position shown in Fig. 3. In the latter position of valve element 32, line 25 communicates with exhaust pipe 24 through the valve V, the drop in pressure in passage 65 causes spring 61 to move valve 56 upward, closing off passage 75 and trapping pressure fluid in bore 30 beneath piston 52, thereby retaining valve element 32 in its upper position. In its upper position, valve element 32 provides communication between in-

take pipe 23 and port 72, whereby pressure fluid passes to the engine E through pipe 27 effecting reverse operation of the stoker engine and stoker.

The trapped pressure fluid beneath piston 52 passes through port 76 and escapes through bleed valve 77 to atmosphere. The bleed valve 77 may be regulated to control escape of pressure fluid so that valve element 32 may be retained in its upper or reverse operating position a predetermined period of time, preferably a length of time sufficient to permit several revolutions of the stoker conveyor screw 19. When the trapped pressure fluid has escaped, piston 52 and valve element 32 descend to the position shown in Fig. 2, again operating the stoker in normal forward direction.

I claim:

1. A control valve for a pressure fluid operated reversible engine, comprising a body member having a valve chamber and a piston chamber, said valve chamber having a pressure fluid intake port and a pair of pressure fluid discharge ports, a movable valve element in said valve chamber providing communication between said intake port and either of said discharge ports, a piston in said piston chamber operatively connected with said movable valve element, means providing a passage from one of said discharge ports to said piston chamber, valve means for opening and closing said passage, yieldable means normally retaining said valve means in a position closing said passage, and means providing a restricted vent from said piston chamber to atmosphere when said valve means is in a position closing said passage.

2. A control valve for a pressure fluid operated reversible engine, comprising a body member having a valve chamber and a piston chamber, said valve chamber having a pressure fluid intake port and a pair of pressure fluid discharge ports, a movable valve element in said valve chamber providing communication between said intake port and either of said discharge ports, a piston in said piston chamber operatively connected with said movable valve element, means providing a passage from one of said discharge ports to said piston chamber, valve means in said passage responsive to the pressure of the fluid in said last named discharge port for admitting pressure fluid to said piston chamber and for closing said passage to trap pressure fluid in said piston chamber, and slow release means for venting pressure fluid from said piston chamber when said valve means is in a position closing said passage.

3. A control valve for a pressure fluid operated reversible engine comprising a body member having a valve chamber and a piston chamber, said valve chamber having a pressure fluid intake port and a pair of pressure fluid discharge ports, a movable valve element in said valve chamber normally providing communication between said intake port and one of said discharge ports, means forming a passage providing communication between said last named discharge port and said piston chamber, a piston in said piston chamber operatively connected with said valve element, and valve means normally closing said passage, said valve means being responsive to a pressure above the normal pressure in said last named port to admit pressure fluid to said piston chamber to move said valve element through said piston to a position providing communication between said intake port and the other of said discharge ports and venting said first named discharge port, said valve means be-

ing responsive to reduction in the pressure in said first named discharge port to close said passage and trap pressure fluid in said piston chamber to retain said valve element in its last named position, and slow release mechanism associated with said piston chamber for releasing the trapped pressure fluid, said valve element being arranged to return to its normal position upon release of the trapped pressure fluid.

4. A control valve for a pressure fluid operated reversible engine comprising a body member having an upper chamber, a lower chamber, a laterally disposed chamber and a passage providing communication between said lateral and lower chambers, said upper chamber having a pressure fluid intake port and a pair of discharge ports, a movable valve element in said upper chamber, a piston in said lower chamber operatively connected with said movable valve element for moving the latter to establish communication between said intake port and either of said discharge ports, said lateral chamber being in communication with one of said discharge ports, and valve means in said lateral chamber responsive to variations in the pressure of the fluid in said last named port for admitting and cutting off flow of pressure fluid to said piston chamber, said piston being responsive to admission of pressure fluid to said piston chamber for moving said movable valve element to a position establishing communication between said intake port and the other

of said discharge ports, and venting said first named discharge port, said valve means being responsive to venting of said first named discharge port to close said passage trapping pressure fluid in said piston chamber to retain said movable valve element in position establishing communication between said intake port and said second named discharge port, and pressure fluid release mechanism associated with said piston chamber for venting pressure fluid, said valve element being responsive to venting of said trapped pressure fluid and returning to position establishing communication between said intake port and said first named discharge port.

5. The combination with a stoker having fuel conveying means and a pressure fluid operated reversible engine for operating said conveying means, of valve mechanism including a movable valve element normally admitting pressure fluid to said engine for operating said conveying means in a forward direction, and including means responsive to an overload on said engine when said conveying means stalls for automatically moving said movable valve element to a position admitting pressure fluid to said engine for operating said conveying means in reverse direction, said last named means including slow release means providing for return of said valve element to its original position.

EUGENE MARTIN.
